US0D1092519S

(12) **United States Design Patent** (10) Patent No.: **US D1,092,519 S**
 Amini et al. (45) Date of Patent: ** Sep. 9, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Mani Amini**, San Jose, CA (US);
Taylor Gerard Carrigan, San Francisco, CA (US); **Chanaka Karunamuni**, Cupertino, CA (US)

(73) Assignee: **Apple Inc.**, Cupertino, CA (US)

(**) Term: **15 Years**

(21) Appl. No.: **29/940,498**

(22) Filed: **May 2, 2024**

Related U.S. Application Data

(63) Continuation of application No. 29/883,975, filed on Feb. 6, 2023, now Pat. No. Des. 1,026,945, which is a continuation of application No. 29/734,622, filed on May 14, 2020, now Pat. No. Des. 977,520, which is a continuation of application No. 29/617,071, filed on Sep. 11, 2017, now Pat. No. Des. 887,443.

(57) **CLAIM**

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design. The dashed broken lines within the peripheral dashed broken line illustrate portions of the graphical user interface, and form no part of the claimed design.
